UNITED STATES PATENT OFFICE

150,115

DESIGN FOR A CHURN

Jack P. Dazey, St. Louis, Mo.

Application August 31, 1946, Serial No. 133,004

Term of patent 7 years

(Cl. D23—1)

To all whom it may concern:

Be it known that I, Jack P. Dazey, a citizen of the United States, residing in the city of St. Louis, State of Missouri, have invented a new, original, and ornamental Design for a Churn, of which the following is a specification, reference being had to the accompanying drawing, forming a part thereof.

In the drawing:

Fig. 1 is a top plan view of a churn, showing my new design;

Fig. 2 is a side elevational view thereof, and

Fig. 3 is another side elevational view thereof.

I claim:

The ornamental design for a churn, substantially as shown.

JACK P. DAZEY.
